UNITED STATES PATENT OFFICE.

MINNIE ISEMAN, OF PITTSBURGH, PENNSYLVANIA, ASSIGNOR TO MARGARETHA A. VIERLING, OF PITTSBURGH, PENNSYLVANIA.

BRUSH ATTACHMENT FOR WASHING MACHINES.

Application filed November 12, 1921, Serial No. 514,533. Renewed January 4, 1927.

This invention relates to a brush attachment for washing machines primarily designed for being secured to the shiftable wringer now commonly used in connection with power washing machines of various types.

Excessively soiled garments cannot be washed clean by most of the power machines now on the market, such garments requiring rubbing upon a washboard, and to eliminate this arduous labor I provide a brush attachment which may be used in connection with a washing machine wringer of any type, and whereby excessively soiled garments may be readily washed with but little labor on the part of the operator.

Further objects of the invention are to provide a device of the character described which may be readily applied to a washing machine wringer without changing the construction of the latter, which is simple in its construction and arrangement, strong, durable and efficient in its use, and comparatively inexpensive to manufacture.

To the accomplishment of these and such other objects as may hereinafter appear the invention consists of the novel construction, combination and arrangement of parts herein specifically described, and illustrated in the accompanying drawings wherein is shown an embodiment of the invention, but it is to be understood that changes, variations, and modifications may be resorted to which come within the scope of the claim hereunto appended.

In the drawings forming a portion of this specification and wherein like numerals of reference designate corresponding parts throughout the several views:—

Figure 1 is a side elevation of a power washing machine embodying my improved brush attachment.

Figure 2 is a front view of the brush attachment secured to the wringer element, the latter being shown in dash lines.

Figure 3 is a top plan view of my improved device.

Figure 4 is a transverse sectional view of the brush roll and associated parts.

Figure 5 is a cross sectional view of the brush roll.

Figure 6 is an end view of the brush roll and associated parts.

Figure 7 is a perspective view of the adjustable support for the scrubbing or backing rollers, with portions broken away.

Figure 8 is a fragmentary perspective view of the backing rollers and associated parts.

Figure 9 is a fragmentary front view of the backing rollers illustrating their connection with the support, the latter being shown in section.

Figure 10 is a vertical sectional view of the motor supporting casing.

Referring in detail to the drawings 1 denotes the tub of a cylinder type washing machine, provided at one corner with the usual vertically disposed housing 2 which encloses the power transmission for operating the wringer element 3.

A brush roll support 4 is positioned horizontally on the front of the wringer element 3 slightly below the contacting portion of the wringer rolls 5. The support 4 is formed to partially enclose the brush roll 6 to prevent the splashing of the water during the operation of the latter.

The top member 7 of the support 4 serves as a guide board for the wringer element 3 to facilitate the feeding of the clothes to the wringer rolls. The member 7 is flat and declines forwardly, as clearly illustrated in Figure 4 of the drawings.

One end of the support 4 is provided with a rearwardly projecting and integrally formed bracket arm 8, and the other end thereof with an adjustable bracket arm 9. The support 4, adjacent to this end, is formed with a longitudinal slot 10 for the passage of the adjusting screw 11 which threadably engages, as at 12, the securing leg 13 of the bracket arm 9. The bracket arm 9 carries a clamping screw 14 for securely attaching the support 4 to the wringer element. By this construction of the bracket arms the support 4 may be conveniently attached to wringer elements of varying widths.

The brush roll 6 is mounted on the shaft 15 which latter is suitably journaled, as at 16, in the end members 17 of the support 4. The brush roll 6 is preferably built in sections to permit of the interchanging or replacement of such sections, thereby eliminating the necessity of discarding the entire brush roll should only sections thereof be

worn from use. One end of the shaft 15 carries a fixed collar 18 provided with a stud 19. One of the brush roll sections abuts against the collar 18 and is provided with an aperture 20 engaging the stud 19, thereby providing for the rotation of the brush roll with the shaft 15. Abutting sections of the brush roll are provided with a dowel 21 engaging alined apertures 22 in respective brush roll sections. The end of the shaft remote from the collar 18 is threaded, as at 23, and engaged by the nut 24, for securely clamping the several sections against the collar 18 and on the shaft 15.

A pair of backing or scrubbing rollers 25 are positioned forwardly of the brush roll 6 and are adapted for holding the clothes against the brush roll during the washing or scrubbing operation. The rollers 25 are rotatably mounted at each end thereof, as shown at 26, in a bearing plate 27, which latter is securely held in position by a tie-rod 28.

Each end of the support 4 is provided with a forwardly projecting arm 29 substantially T-shaped in transverse cross section. A carrier 30 is slidably mounted on each of the arms 29 in a manner clearly illustrated in Figure 7 of the drawings. Each of the carriers 30 is formed with a bearing aperture 31 for the reception of the stud 32 carried by the bearing plates 27, thereby pivotally connecting the rollers 25 with the carriers 30. The aperture 31 in each of the carriers 30 is tapered inwardly, as at 33, to provide and compensate for a vacillatory movement concomitant to the operation of the rollers 25 due to the unevenness of the bulk of clothes washing.

Each of the arms 29 is formed with a vertically disposed portion 34 provided with a threaded aperture 35 for the engagement of the tensioning screw 36. The inner end of the tension screw 36 carries a coil spring 37 which extends into the pocket 38 formed in the enlarged end of the carrier 30. By the adjustment of the screws 36 the rollers 25 may be tensioned against or released from the brush roll 6.

The shaft 15 is provided with an exten-

sion 39 which carries the pulley 40, fixed thereto.

A casing comprising two sections 41 and 42 respectively, is securely clamped to the upper end of the transmission housing 2, by means of the bolt 43. The contour of the inner wall of the sections 41 and 42 is identical to the contour of the outer face of the upper end of the transmission housing 2 over which the said sections are clamped. The section 41 of the casing is formed with a bracket 44 and supports the motor 45 secured thereon. The motor 45 is provided with a drive pulley 46 which is connected with the pulley 40 through the transmission belt 47.

In the operation of my improved brush attachment the clothes to be washed are positioned between the brush roll 6 and the scrubbing or backing rolls 25. The action of the brush roll will tend to feed the clothes between the brush roll and the backing rollers, but the clothes may be held by the operator and retard such feeding action, thereby permitting the washing or scrubbing of any portion of the clothes which may be excessively soiled until thoroughly cleaned. When the garment has been almost fed past the brush roll, the end thereof may be started through the wringer element whereby the garment is automatically drawn back over the brush roll and through the wringer. The brush roll, rotating in the clockwise direction and at considerable speed, will provide an intense scrubbing action during such return movement of the garment. The operation may be repeated as often as found necessary and the garment turned and reversed on successive operations.

What I claim is:

A scrubbing attachment for washing machines comprising a support in the form of a housing, rotatable scrubbing elements carried by the support, and means carried by the support for detachably connecting said support to a wringer, the upper portion of said housing constituting a guide.

In testimony whereof I affix my signature.

MINNIE ISEMAN.
